UNITED STATES PATENT OFFICE.

CHARLES J. AHRENFELDT, OF NEW YORK, N. Y.

DESIGN FOR A PLATE.

SPECIFICATION forming part of Design No. 24,375, dated June 11, 1895.

Application filed January 15, 1895. Serial No. 535,034. Term of patent 7 years.

To all whom it may concern:

Be it known that I, CHARLES J. AHRENFELDT, a citizen of the United States, residing at New York city, county and State of New York, have invented and produced a new and original Design for a Plate, of which the following is a specification, reference being had to the accompanying drawings, forming a part thereof.

10 Figure 1 is a plan view of a plate embodying my design. Fig. 2 is an edge view of the same half cut away and showing a diametrical cross-section.

15 The leading feature of my design is a line of leaf-shaped ornamentation extending wreath-

like around the plate in a line parallel to and a short distance inside of the periphery.

A is the periphery of the plate and B is the leaf-shaped ornamentation, which is circular in form and is situated on the bevel of the abrupt depression on the interior surface of the plate.

What I claim is--

The design for a plate, substantially as herein shown and described.

CHARLES J. AHRENFELDT.
